UNITED STATES PATENT OFFICE.

GEORGE F. MAYER, OF CHICAGO, ILLINOIS.

LOCK.

Application filed May 31, 1923. Serial No. 642,389.

To all whom it may concern:

Be it known that I, GEORGE F. MAYER, a citizen of the United States, residing at Chicago, in the county of Cook and State of Illinois, have invented certain new and useful Improvements in Locks, of which the following is a specification.

My invention relates to locks and has particular reference to a keyless lock adapted primarily for the fastening of doors and the like and in which selective operative means are provided extending to the outer side of the door by means of which any one familiar with the particular combination is able to open the lock, and which also has a common operating means extending to the inner portion of the door so that the locking means can be released for opening the door from the inside.

Another object of my invention is the provision of a keyless lock which is extremely simple in operation and operates quickly and easily by one familiar with the particularly selective operative means employed for unlocking the bolt or which can be made more secure through the operation of the said selective means after the lock is bolted in position by means of the locking tumblers and also which when tampered with by any one unfamiliar with the particular combination of selective operating parts succeeds in placing additional locking tumblers in the path of the locking bolt so the lock is more securely fastened in position.

Another object of my invention is the provision of a keyless lock which is simple in operation and which has its selective operating parts so arranged that they may be changed at will so that an infinite number of combinations can be arranged for unlocking the lock if desired.

Another and further object of my invention is the provision of a lock which, after being locked in position from the inside of the door by the common locking means, can be securely fastened against operation from the outside by locking the selective means and which performs the function of a night lock in addition to its ordinary locking function and which serves to securely lock the selective operating means against operation by any one on the outside of the door.

These and other objects of my invention will be more fully and better understood by

reference to the accompanying sheets of drawings, and in which—

Figure 1 is a vertical elevational view of a section of a door showing the selective operative means extending therethrough;

Figure 2 is a vertical elevational view of the rear portion of a lock showing the common tumbler operating means and also the selective locking member projecting therethrough;

Figure 3 is a vertical sectional view through a door showing my improved lock in position in a door;

Figure 4 is a plan view partially in section showing the locking bolt and locking tumblers in position;

Figure 5 is a transverse vertical sectional view on line 5—5 of Figure 4;

Figure 6 is a transverse vertical sectional view on line 6—6 of Figure 4;

Figure 7 is a transverse sectional view on line 7—7 of Figure 4;

Figure 8 is a transverse vertical sectional view on line 8—8 of Figure 4;

Figure 9 is a longitudinal vertical sectional view on line 9—9 of Figure 4;

Figure 10 is a perspective view of one of the locking tumblers hereinafter designated as a class A tumbler;

Figure 11 is a perspective view of one of the tumblers hereinafter designated as a class B tumbler;

Figure 12 is a perspective view of one of the tumblers hereinafter designated as a class C tumbler;

Figure 13 is a perspective view of the locking bolt;

Figure 14 is a perspective view of the outer end of the locking bolt operating bar; and

Figure 15 is a perspective view of the inner end of the locking bolt operating bar.

Referring now specifically to the drawings; and in which like reference characters refer to like parts throughout, a section of a door 10 is shown having the usual latching mechanism 11 mounted therein operated by an inner knob 12 and an outer knob 13, which form no part of my present invention, and having a lock casing designated as a whole as 14 mounted therein and which has an inner plate 15 and an outer plate 16 secured to the door in the usual manner, the outer plate 16 having a plurality of openings 17, 17 therein through which the outer

60

ends of the selective tumbler operating plates hereinafter described project. Referring now to the lock designated as a whole as 14, I provide an upper casing 18 rectangular in shape, and a lower casing 19 also rectangular in shape, the upper casing having an ear 20 secured thereto by means of which the said lock is fastened to the door 10 by means of a screw 21 when placed 10 permanently in position upon the door. The upper casing 18 may be secured to the lower casing 19 in any approved manner by being hinged thereto by a pair of pivotally mounted straps or hooks 22, 22 pivotally secured to the upper casing 18 and engaging upon screws 23, 23 secured to the lower casing 19 of the lock. The upper casing 18 of the lock has mounted therein a plurality 15 of selective sliding operating plates 24, 24, 20 each of which pass through the forward wall 25 of the casing 18 and have round inner portions 26, the forward ends of which project through a transversely extending wall 27 intermediate the side members 25 and 28 of the casing 18 of the lock. Mounted between the walls 25 and 27 upon 25 the round portions 26 of the plates 24 is a plurality of coiled compression springs 29 which perform the function of holding the tumbler operating plates 24 in their outward position except when pressure is applied thereto. Each of the plates 24 has a downwardly extending arm 30 integrally formed therewith and which extends downwardly into the lower casing 19 of the lock 30 and behind the sliding locking tumblers, which will be described hereinafter, these members forming the selective operating means for controlling the locking bolt, as 35 will be hereinafter described. Extending transversely of the upper casing 18 and between the intermediate wall 27 and the rear wall 28 is a slidably mounted plate 31 which abuts against the wall 27 and against 40 the rear ends of the plates 24 and which is controlled by a push button 32 having a coil spring 33 interposed between the rear wall 28 and the head of the push button 32, the push button 32 having a member 34 on the inner end thereof with a collar 35 secured to the shaft 36 of the push button and which has a shoulder 37 thereon, so that when the push button 32 is pushed inward the plate 31 abuts against the inner 45 end of the shaft portions 26 of the members 24 and is locked in this position by pushing the button to one side or the other so the shoulder 37 engages against the inner side of the plate 28 and the end of the member 35 is in engagement with the wall 28, thus effectively locking the lever 24 against movement and forming in effect a night lock and preventing any one from operating the locking bolt by means of the push 50 levers 24.

The lower casing 19 is composed of a U-shaped member having upstanding end portions 38 and 39 with a bottom portion 40, integrally formed with the said end portions 38 and 39, the said end portions being inturned at the sides to form retaining members 41 for the ends of the side members 42 and 43, thus forming a rectangular shaped open topped casing within which the locking bolt, locking bar and tumblers are contained, as will be more fully described hereinafter. Centrally positioned with respect to the lower casing 19 is a longitudinally extending locking bar 44 having a plurality of upstanding spaced teeth 45, 45, 50 therein, the teeth extending in longitudinal rows on each side of a longitudinally extending channel 46 formed in the locking bar 44 between the teeth 45, 45 and within which is positioned a locking bolt 47, the locking bolt 47 also having a plurality of upstanding teeth 48 thereon and which is adapted to slide in longitudinal movement in the channel 46 and between the rows of teeth 45, 45. The member 47 has an outwardly projecting end 48a which is adapted to abut against the rear end of a lock stem 49 having a button 50 positioned thereon, the lock stem having a locking member 51 on the outer end thereof. A U-shaped member 52 is secured to the door casing within which a compression spring 53 is mounted, one end of which abuts against a collar 54 and is secured to the member 49 so that the expansive force of the spring is exerted 55 against the member 48a and serves to withdraw the latch 51 from the usual latch opening in the side of the door facing unless held in locked relation by means of the locking bolt 47, as will be more fully described 60 hereinafter.

The member 44 is supported upon filler blocks 55, 55, upon the bottom 40 of the lower casing 19 of the lock, and has screws 56, 56 extending into the said filler blocks 60 and which secures a plate 57 to the bottom 40, spacers 58, 58 being provided between the plate 57 and bottom 40 forms a housing for a locking bolt operating member 61 designated as a whole as 59 and which is composed of an outer member 60 and an inner member 61 illustrated in detail in Figures 14 and 15. The locking bolt 47 has a downwardly extending portion 62 having a square opening 63 therein through which the shank 64 on the member 60 extends, the said shank 64 also extending between the portions 65 and 66 of the member 61, the said member 62 also extending downwardly through a slot 67 formed in the locking bar 44 and also through slots 68 and 69 formed in the members 57 and 40 respectively. The member 60 has a pair of side portions 70 and 71 against which the ends of the member 65 and 66 abut during the normal opera- 70 75 80 85 90 95 100 105 110 115 120 125 130

tion of the lock and has a channel 72 formed therein within which the outer side wall member 42 is seated. The member 61 has a recessed portion 73 in the upper face thereof with an inwardly extending end portion 74 which is spaced upwardly a short distance from the upper edges of the members 65 and 66 forming a recess within which the casing 43 is adapted to be seated, the member 61 being capable of inward and outward movement for purposes of operating the locking bolt from the inside of the door.

Centrally mounted at the rear of the casing 19 upon a shaft 75 and extending longitudinally of the casing 19 for its entire length is a wing member 76, the said shaft 75 being mounted in blocks 77^a and 78^a in recesses formed in posts 77 and 78 in each end of the casing 19 and on each side of the locking bar 44. At the front of the casing 19 and extending longitudinally thereof is a second shaft 79 mounted in a pair of sliding blocks 80 and 81 which in turn fit into recesses formed in stationary blocks 82 at each end of the member 19, the said shaft 79 having a pair of pivotally mounted wings 83 and 84 mounted thereon which form a part of the tumbler operating mechanism for controlling the sliding locking bolt 47 relative to the locking bar 44.

The locking and unlocking of the locking bolt 47 with respect to the locking bar 44 is accomplished by means of a plurality of sliding tumblers which extend transversely of the locking bar 44 between the teeth 45, 45, designated as a whole as 85, 85, these tumblers comprising three classes which, for convenience, will be designated as an A, or a locking tumbler, illustrated in detail in Figure 10, a B tumbler, illustrated in detail in Figure 11, and a C tumbler, illustrated in detail in Figure 12. The A or locking tumbler has a locking portion 86 with a notch 87 on one side thereof, with a down-turned portion 88 at one end thereof and a similar down-turned portion 89 at the opposite end thereof, this tumbler being placed at any desired position between the teeth 45, 45 on the member 44 and extending transversely there-across with the down-turned portion 89 of the A tumbler engaging the upper edge of the wing 83 with the opposite end of this tumbler extending beyond and riding upon the upper edge of the wing 76, illustrated particularly in detail in Figure 6, wherein the A tumbler is shown in normally locked position. Extending longitudinally of the casing 19 at the rear portion thereof is a spring mounted plate 90 carried by a plate 91 having posts 92, 92 mounted therein and around which expansion springs 93, 93 are positioned so that the force of the springs 93 is exerted inwardly against the plate 90 which slides upon the posts 92 and

which is prevented from becoming disengaged from the said posts by heads formed thereon and which holds the locking portion 86 of the A tumbler between a pair of teeth 48 on the locking bolt 47 in the normal operation of the device, and until released by a movement of a locking plate 24 at the front or a movement of the locking bolt 61 at the rear, so that this tumbler is always held in normally locked position until released by an inward movement transmitted to the locking tumbler through the medium of the push plate 24 and down-standing portions 30 which extend behind the A tumbler and push the locking portion 86 out of engagement with the teeth 48, whereupon if the locking bolt 47 is in locked position the spring 53 will throw the locking bolt 47 back into unlocked position providing the tumblers hereinafter described have been properly positioned with respect to the locking bolt 47.

As an additional locking element to the A tumbler, hereinabove described, I provide a C tumbler, illustrated in detail in Figure 12, and which comprises a transversely extending portion 94 having a notch 95 therein and a locking portion 96 with a down-standing leg portion 97 which extends into sliding engagement with the bottom member 40, as illustrated in Figure 5, and in which this tumbler is shown in normally unlocked position, and under the control also of one of the push plates 24 in the same manner as has been heretofore described with respect to the A or locking tumbler. The purpose of this tumbler is, as stated above, to provide additional locking means, and is operated by pushing upon the selective push plate 24 which the operator knows is connected to this C tumbler, and which has the effect of pushing the locking portion 96 into the path of the teeth 48 in the locking bolt 47, where the C tumbler remains and serves as an additional locking element for the locking bolt 47 until released by the operator by pushing the proper selective plates to use in unlocking the locking bolt 47 and has the effect of pushing the C tumbler into locked relation, thus serving to more securely fasten the locking bolt 47 in locked relation.

It will be noted that the upper edge of the wing 83 is engaged in the notch 95 in the lower portion of the C tumbler. The C tumbler also serves the function of preventing the unlocking of the device by pushing the push plates promiscuously by any one not knowing the proper selective plates to use in unlocking the locking bolt 47 and has the effect of pushing the C tumbler into locked relation, thus serving to more securely fasten the locking bolt 47 in locked relation.

For the purpose of controlling the C tumbler and bringing it into unlocked position, I provide a sliding B tumbler, illustrated

in detail in Figure 11, and shown particularly in combination in the lock in Figure 7, this tumbler having a body portion 98 and an elongated leg portion 99 extending downwardly and ordinarily in sliding engagement with the bottom member 40 of the member 19, and having a pair of downwardly projecting portions 100 and 101 with a channel 102 formed therebetween through which the teeth 48 on the sliding bolt 47 move in normally unlocked relation with this tumbler.

It will be noted that the leg portion 99 extends over the wing 83 on the outside thereof to the bottom member 40 and in position to engage the wing 83 at the bottom thereof. When the C tumbler (see Figure 5), is pushed into locked relation the wing 83 is turned into an angular position instead of vertical, as illustrated in Figure 5, so that when the C tumbler is in locked relation the wing 83 is engaged in the notch 95 and therefore in order that this tumbler may be brought into unlocked relation it is necessary to bring it back into the position shown in Figure 5. This is accomplished by the operator making a proper selection of the sliding plates 24 controlling the B tumbler which, when pushed in, has the effect, because of the leg portion 99 engaging against the lower portion of the wing 83, of bringing the C tumbler back into the position shown in Figure 5, or into an unlocked position, so that the locking bolt 35 is released by the operator pressing upon the proper push levers leading to the A or unlocking tumbler.

The unlocking operation heretofore described may be made more complicated by the addition of as many of the locking tumblers as may be desired and the lock thereby becomes more difficult of operation by any one not having a proper knowledge of the proper combination of push levers to operate, it being understood that any of series B tumblers must be provided for operating the C tumblers and these two tumblers must be connected to the same pivotal wing, but that the operation of the device will always remain the same.

In the illustration (Figure 4), are shown four tumblers of the C type placed in position over the edge of the wings 83 and 84 with a class B tumbler also shown in proper position to control the two type C tumblers by engagement with the bottom of the wings 83 and 84 when the push levers controlling these tumblers are operated, and also with two A or locking tumblers also shown in position. These tumblers may be positioned in any manner with respect to the push levers which have been heretofore described and which project through the outer plate 16 with numbers appearing above the combinations so that the device can be

properly operated from the outside as long as the B and C tumblers are placed in co-operating relation with each other on the same wing. This same series of tumblers is also shown connected to the wing 84 so that in the lock as illustrated there are eight push levers which control the eight sliding tumblers illustrated in Figure 4, and the relation of these tumblers with respect to the selective push levers operating the same may be varied at will.

It will also be understood that upon the operator releasing any push lever connected to the B tumbler, the springs 93 will cause the B tumbler to be returned to unlocked position when the push lever is relieved of pressure.

When it is desired by the operator to position the lock in locked position from the outer side of the door, it being assumed that the B and C tumblers are in unlocked position, he presses upon the plate 24 or pair of plates 24, as the case may be, connected to the locking tumblers A and slides the locking bolt forward by means of the member 60, and thereupon releases the pressure upon the plates controlling the A tumblers which immediately, because of the pressure of the springs 93, are forced back into locked position, as shown in Figure 6. If the operator desires to lock the bolt further he pushes the plates connected to the sliding tumblers C which are thereupon pushed into locked relation and, upon returning and desiring to unlock the bolt, he first pushes the plates leading to the B tumblers which has the effect, as heretofore described, of bringing the C tumblers back into unlocked position and thereupon by pushing the selective plates controlling the A tumblers, the locking bolt is thrown back by the spring 53 and the lock unfastened.

It will be noted that extending through the lock on the inner side thereof is the member 61 which engages against the bottom of wing 76, at the top of which engages the projections 88 on the A tumblers and at the bottom of which is in position to engage the lower portion of the down-standing legs 97 of the C tumblers. It will therefore be understood that by pushing inwardly upon the member 61 the wing 76 is turned into an angular position and the A tumblers are pulled forward into unlocked position and the C tumblers, if they are in locked position, are pushed backward into unlocked position and if they are not in locked position are not affected in any way by the wing 76, but the bolt 47 is released by the A tumblers, which is thrown back by the spring 53 into unlocked position. Conversely, if it is desired to lock the device from the inside the locking tumblers are aligned by an inward pressure on this member and the locking bolt moved forward and held

while the pressure on the member 51 is released, allowing the A tumblers to slide into locked relation and positioning the sliding bolt into locked relation.

5 As heretofore described, if it is desired to fasten the lock as a night lock, push button 32 is pushed inward and locked, preventing any inward movements of the plates 24, which control the sliding tumblers, as 10 heretofore described.

Positioned at one side I provide a pair of springs 103 and 104 positioned between the blocks 80 and 81 and which allow for a slight movement of the side without moving 15 the tumblers in any way, or having any effect upon their operation, which might be possible if these springs were not so employed.

The operation of the device will be understood by those skilled in the art from the foregoing description and it will be further understood that the parts may be duplicated any number of times desired, so as to make the operation of the lock more difficult by one not having knowledge of the 20 particular buttons which control the tumblers and in sequence of their operation, but the description given above will apply to such repetition of parts.

30 While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. A lock comprising, in combination, a 40 fixed locking bar having a plurality of spaced teeth thereon, a sliding locking bar adapted to cooperate with said fixed bar, a plurality of locking tumblers and means associated with said tumblers adapted to hold the said tumblers in normally locked position.

2. A lock comprising, in combination, a 50 fixed locking bar having rows of spaced teeth thereon, a sliding locking bar positioned between the rows of spaced teeth and adapted to cooperate with said fixed bar, a plurality of locking tumblers sliding between the teeth on the said fixed bar, and a spring pressed plate adapted to hold the said tumblers in normally locked position.

3. A lock comprising, in combination, a 60 fixed locking bar having rows of spaced teeth projecting upward therefrom, locking tumblers adapted to cooperate with said locking bar, unlocking tumblers carried by said locking bar and means adapted to cooperate with said unlocking tumblers to position said locking tumblers in unlocked position.

4. A lock comprising, in combination, a

fixed locking bar having rows of teeth thereon, a sliding locking bar adapted to cooperate with said fixed bar, a plurality of locking tumblers associated with said locking bar, a plurality of unlocking tumblers and a pivotally mounted wing adapted to form a connection between said unlocking tumblers and said locking tumblers whereby the said unlocking tumblers will move the said locking tumblers into unlocked position. 70

5. A lock comprising, in combination, a casing, a locking bar fixedly mounted therein and having a plurality of upstanding projecting teeth thereon, a locking bolt in sliding cooperative relation with said locking bar, a plurality of locking tumblers extending across said locking bar and between said teeth and in engagement with the said locking bolt, selective operating means for controlling said tumblers from one side of said lock, and common tumbler operating means extending to the other side of said lock. 80

6. A lock comprising, in combination, a casing, a locking bar fixedly mounted therein and having a plurality of upstanding projecting teeth thereon, a locking bolt in sliding cooperative relation with said locking bar, a plurality of locking tumblers extending across said locking bar and between said teeth and in engagement with the said locking bolt, selective operating means for controlling said tumblers from one side of said lock, and common tumbler means extending to the other side of said lock, and independently controlled means adapted to lock said selective operating means against movement. 90

7. A lock comprising in combination, a casing, a locking bar fixedly mounted therein and having a plurality of teeth thereon, a locking bolt in sliding cooperative relation with said locking bar, locking tumblers extending across said locking bar and between said teeth and having means thereon for engagement with said locking bolt, selective tumbler operating means extending to the outside of said lock controlling said tumblers, a locking plate positioned in abutting relation with said selective tumbler operating means, and means for holding said locking plate in engagement with said selective tumbler operating means. 100

8. A lock comprising, in combination, a casing, a locking bar fixedly mounted therein and having a plurality of teeth thereon, a locking bolt in sliding cooperative relation with said locking bar, locking tumblers extending across said locking bar and between said teeth and having means thereon for engagement with said locking bolt, selective tumbler operating means extending to the outside of said lock controlling said tumblers, a locking plate positioned in abutting relation with said selective tumbler operat- 110 115 120 125 130

ing means, and a locking button adapted to hold said plate in abutting engagement with the selective tumbler operating means.

9. A lock comprising, in combination, a casing, a locking bar fixedly mounted therein and having a plurality of teeth thereon, a locking bolt in sliding cooperative relation with said locking bar, locking tumblers extending across said locking bar and between said teeth and having means thereon for engagement with said locking bolt, means for normally holding said locking tumblers in locked relation with said bolt, and selective tumbler operating means adapted to unlock said tumblers.

10. A lock comprising, in combination, a casing, a locking bar fixedly mounted therein and having a plurality of teeth thereon, a locking bolt in sliding cooperative relation with said locking bar, locking tumblers extending across said locking bar and between said teeth and having means thereon for engagement with said locking bolt, spring controlled means adapted to normally hold said locking tumblers in locked relation with said bolt, and selective tumbler operating means adapted to unlock said locking tumblers.

11. A lock comprising, in combination, a casing, a locking bar fixedly mounted therein and having a plurality of teeth thereon, a locking bolt in sliding cooperative relation with said locking bar, locking tumblers extending across said locking bar and between said teeth and having means thereon for engagement with said locking bolt, a spring pressed plate adapted to normally hold said locking tumblers in locked relation with said bolt and selective tumbler operating means adapted to unlock said tumblers.

12. A lock comprising, in combination, a casing, a locking bar fixedly mounted therein and having a plurality of teeth thereon, a locking bolt in sliding cooperative relation with said locking bar, locking tumblers extending across said locking bar between said teeth and having means thereon for engagement with said locking bolt, a plurality of other tumblers extending across said locking bolt and selective means for controlling said locking tumblers and said second mentioned tumblers.

13. A lock comprising, in combination, a casing, a locking bar fixedly mounted therein and having a plurality of teeth thereon, a locking bolt in sliding cooperative relation with said locking bar, locking tumblers extending across said locking bar and in engagement with said locking bolt when in locked position, a second set of locking tumblers extending across said locking bar and held in normally unlocked relation with said locking bolt and a plurality of tumblers adapted to control said second mentioned locking tumblers and selective operating

means controlling all of said locking tumblers.

14. A lock comprising, in combination, a casing, a locking bar fixedly mounted therein and having a plurality of teeth thereon, a locking bolt in sliding cooperative relation with said locking bars, spring compressed locking tumblers extending across said locking bar and held in locked position with said locking bolt, a second set of locking tumblers normally held out of locked relation with said locking bolt, a plurality of tumblers controlling said last mentioned locking tumblers, a pivotally mounted wing member with which said second mentioned locking tumblers and said locking tumblers are in engagement and selective operative plates for controlling the operation of said tumblers.

15. A lock comprising, in combination, a casing, a locking bar fixedly mounted therein and having a plurality of teeth thereon, a locking bolt in sliding cooperative relation with said locking bar, locking tumblers extending across said locking bar and in normal engagement with said locking bolt, selective operating levers directly controlling the said locking tumblers, a second set of locking tumblers normally out of locked relation with said locking bolt, selective operating plates adapted to move said second tumblers into locked relation with said locking bar and unlocking plates extending across said locking bar and arranged to move said second mentioned locking tumblers into unlocked relation with said bolt.

16. A lock comprising, in combination, a casing, a locking bar fixedly mounted therein and having a plurality of teeth thereon, a locking bolt in sliding cooperative relation with said locking bar, locking tumblers extending across said locking bar and in normal engagement with said locking bolt, a pair of pivotally mounted wing members extending longitudinally of said lock casing, a second set of locking tumblers in engagement with one of said wings, selective operating plates adapted to push said second mentioned locking tumblers into locked relation with said bolt, unlocking tumblers co-acting with said wing to unlock said second mentioned locking tumblers and selective means for controlling the operation of said unlocking plates.

17. A lock comprising, in combination, a casing, a locking bar fixedly mounted therein and having a plurality of teeth thereon, a locking bar in sliding cooperative relation with said fixed locking bar, locking tumblers extending across said locking bar and in engagement with said locking bolt, a plurality of unlocking tumblers and means connecting said unlocking tumblers with said locking tumblers adapted to collectively po-

sition all of the locking tumblers in unlocked relation with said locking bolt.

18. A lock comprising, in combination, a casing, a locking bar fixedly mounted therein having a plurality of teeth thereon, a locking bolt in sliding cooperative relation with said locking bar having a downwardly extending projection thereon, a two piece operating bar for said locking bolt, a plurality of locking tumblers extending

transversely across said locking bar, selective operating means controlling said tumblers from the outside of the lock and a wing member in engagement with said operating bar and controlling the operation of the said tumblers from the inside of the lock. 15

Signed at Chicago, Illinois, this 28th day of May, 1923.

GEORGE F. MAYER.
